UNITED STATES PATENT OFFICE

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK

YARN CLEANER

Application filed July 31, 1928. Serial No. 296,477.

This invention relates to yarn cleaners for removing impurities from traveling yarns, and aims to provide a simple and effective device for detaching specks and other impurities from a traveling yarn which automatically adjusts itself for yarns of different sizes.

The invention is particularly adapted for use in the scraping type of yarn cleaner in which a traveling yarn is drawn between two opposed members, one or both of which exert a scraping action on it. In accordance with the present invention, one of the two opposed members is mounted so as to be movable with respect to the other during the operation of the cleaner. The movable member has a mass such that its inertia prevents it from making other than very slight outward movements when urged outwardly by irregularities on the yarn. The movable member is constantly urged inwardly toward the yarn by a force very much less than its weight. Consequently, after it has been moved slightly outward by irregularities of the yarn, it moves inwardly against the yarn again, but with a force so slight that it does not exert undue pressure on the yarn which would tend to tear it.

This construction, besides having the important advantage of making the cleaner self-adjusting for yarns of different sizes, has the additional advantage of increasing the effectiveness of the cleaning because of the slight inward and outward vibration of the movable member which occurs when the device is in operation.

The nature of the invention may be more fully understood from a detailed description of the three embodiments of it which are illustrated in the accompanying drawings, in which:

Fig. 1 is a side elevation of a yarn cleaner embodying the invention with part of the collecting receptacle broken away;

Fig. 2 is a plan view of the cleaner shown in Fig. 1;

Fig. 3 is a side view of this cleaner looking in the direction of the arrow 3 in Fig. 4 and showing the frame of the yarn cleaner sectioned on the line of travel of the yarn;

Fig. 4 is an enlarged transverse section taken on the line 4—4 of Fig. 2;

Fig. 5 is an enlarged transverse section taken on the line 5—5 of Fig. 2;

Fig. 6 is a plan view of a second yarn cleaner embodying the invention with part of the collecting receptacle broken away;

Fig. 7 is a side view of the cleaner shown in Fig. 6 looking in the direction of the arrow 7 in Fig. 8 and showing the frame of the cleaner sectioned on the line of travel of the yarn;

Figs. 8 and 9 are enlarged transverse sections taken on the lines 8—8 and 9—9 of Fig. 6 respectively;

Fig. 10 is a transverse section similar to Fig. 5 showing a third cleaner embodying the invention; and

Fig. 11 is a transverse section similar to Fig. 5 showing a fourth cleaner embodying the invention.

The yarn cleaners illustrated are intended to operate upon a traveling yarn which is being drawn from a bobbin or cone into a winding, spooling, or other machine. The cleaners may be conveniently secured to a portion of the frame of any such machine.

The yarn cleaners shown in Figs. 1 to 5 inclusive are provided with a supporting bar 10 having a bracket 11, in the lower edge of which is a vertical slot adapted to fit over a horizontal bar B forming a part of the frame of a winding or other machine. A set screw 12 is provided to hold the supporting bar 10 firmly on the bar B. The mounting is such that the upper surface of the supporting bar is in a horizontal plane. One of the side surfaces 13, which, for convenience, is termed its inner side, is inclined at an angle of about 15° to the vertical.

To the inclined surface 13 of the supporting bar 10 is attached the fixed side member 20 of the frame of the yarn cleaner. The attachment may be by means of screws 16. The frame of the yarn cleaner has also a movable side member 30 which has near its ends holes which fit loosely around studs 17 projecting from the fixed member 20 near its ends. The fixed side member 20 is rectangular in cross section, and studs 17 pro-

ject perpendicularly from its inner side so that they are inclined upwardly at an angle of about 15° to the horizontal. Consequently, the movable side member 30 tends to slide in toward the fixed side member 20 under the force of gravity, but the force thus tending to urge it inwardly is only a small fraction of its weight.

Both the fixed and movable sides 20, 30 are provided with transverse rearwardly inclined scraping blades 21, 31 permanently set in inclined slots 22, 32 in the inner sides of said members. Each blade 31 is co-planer with one of the blades 21, and the blades are provided with opposed scraping edges 23, 33. As appears most plainly in Fig. 5, the scraping edges 23, 33 of each pair of blades have middle portions 24, 34 which are substantially parallel and have outwardly curved upper portions 25, 35 and outwardly curved lower portions 26, 36. One set of the scraping edges, for example, the set 23, are provided with small aligned notches 27 located at the upper ends of the intermediate portions 24. The lower edges of these notches are aligned with the upper surfaces of the studs 17 and the upper surface of a pin 18 projecting from the fixed side member 20.

In order to guide a yarn A between the scraping edges 23, 33, thread guides 40, 41 are provided at opposite ends of the frame of the cleaner, being supported on brackets projecting inwardly from the supporting bar 10.

A tension device 42 is also provided on the front thread guide 40, and an adjustable slab catcher 43 may be provided between the thread guide 41 in the rear end of the frame of the cleaner. In the form shown, the slab catcher 43 consists of a table 44 formed on a bracket projecting inwardly from the supporting bar 10 and a blade 45 carried by a bracket 46 projecting inwardly from the upper part of the bar 10. The upper portion 47 of the bar 10 to which the bracket 46 is attached is separated from the main portion of the bar by a slot 48, so that it may be moved up and down by means of an adjusting screw 49 to vary the distance between the blade 45 and the table 44.

The use and operation of the cleaner as described is as follows: The cleaner is threaded by passing a yarn A through the thread guide 40 and under the tension device 42 and dropping it into the space provided between the curved upper portions 25, 35 of the scraping edges 23, 33 of the blades, passing it over the table 44 and under the blade 45 of the slab catcher and then over the thread guide 41. As soon as a pull is applied to the yarn beyond the thread guide 41, the yarn is drawn down until it strikes the studs 17 and pin 18, and is thus positioned between the notches 27 of the blades 21 and scraping edges 33 of the blades 31. As the yarn is thus drawn down, it, of course, causes a slight outward

movement of the movable side member 30 and its blades 31; for, before the cleaner is threaded, the movable member 30 slides in so that the intermediate portions 34 of the scraping edges are in contact with the intermediate portions 24 of the fixed scraping edges.

In the operation of the cleaner, the yarn is drawn from left to right (Figs. 1, 2, 3). As the yarn is drawn through the cleaner, the specks and other impurities which it contains and a slight amount of fibrous matter, are scraped from it by the blades. The particles removed, which are, of course, traveling rapidly in the same direction as the yarn when they are scraped off, are directed downwardly by the lower portions of the blades. During the travel of the yarn, specks and other slight irregularities of the yarn cause frequent and irregular forces on the blades 31 carried by the movable member 30, which set this member and its blades into an inward and outward reciprocation of very small amplitude. This reciprocation, or vibration as it may be termed, tends to keep the blades clear of fibrous matter. At not infrequent intervals, the reciprocation is momentarily of sufficient amplitude to permit the yarn to slip out of the notches 27 and move downwardly between the blade edges, thus clearing out any fibrous matter or particles which may have been caught between the blade edges below the yarn.

It is apparent from the above description that the cleaner which is described is self-adjusting for yarns of different sizes, since the distance between the opposed scraping edges is determined by the yarn itself. It is, however, sometimes desirable to provide the device also with a manual adjustment, limiting the extent to which the opposed scraping edges may approach one another. Such an adjustment is provided in the cleaner illustrated by screws 50 and threaded in tapped holes in the studs 17 and stops 51 formed on brackets 52 attached to the movable member 30 and adapted to limit the inward movement of the yarn by engagement with the heads of the screws 50. The heads of these screws serve to prevent accidental removal of the side member 30 from the studs 17.

The yarn cleaner shown in Figs. 6 to 9 inclusive is similar to that already described, except that its movable side 30' carries no blades, but instead is provided with a smooth surface 31' opposed to the scraping edges 23' of the blades 21'. A detailed description of this cleaner is unnecessary as its construction is apparent from Figs. 6 to 9 of the drawings in which the parts corresponding to the first cleaner described are correspondingly numbered. Like the first cleaner described, the second cleaner is self-adjusting. It is apparent that the operation of this cleaner is

similar to that of the first cleaner, since its movable member 30 is similarly set into a small amplitude reciprocation during the travel of the yarn.

- 5 The cleaner shown in Fig. 10 is similar to the first cleaner described, except that its frame is set in a horizontal plane, so that its studs 17² are horizontal and its movable side member 30² is not urged inward by gravity. An equivalent effect is, however, obtained by means of long light compression springs 53 reacting between heads 54 at the ends of the studs 17² and the outer surface of the movable side member 30², urging 15 said member inwardly with a force which is equal to only a small fraction of its weight. It is apparent that the operation of this cleaner is substantially like that of the first cleaner described.
- 20 The cleaner shown in Fig. 11 is similar to that shown in Fig. 10 except that both of its side members 20³ and 30³ are movable. The two side members are slidably mounted on long studs 17³ projecting horizontally from 25 the supporting bar 10. The side members are urged towards each other by long light compression springs 53', 54 each of which exerts the force equal to only a small fraction of the weight of the side member against which it 30 re-acts.

What I claim is:

1. A yarn cleaner for removing particles from a traveling yarn, comprising opposed separable members at opposite sides of the 35 yarn, at least one of which is provided with transverse scraping edges, and means for yieldably urging one of said members against the yarn by a force materially less than the weight of the movable parts of the cleaner.
- 40 2. A yarn cleaner for removing particles from a traveling yarn, comprising a frame member at one side of the yarn, a massive movable member opposed thereto at the other side of the yarn, at least one of said members 45 being provided with transverse scraping edges, and the movable member being yieldably urged against the yarn by a force materially less than the weight of the movable member.
- 50 3. A yarn cleaner for removing particles from a traveling yarn, comprising a frame member at one side of the yarn, a massive movable member opposed thereto at the other side of the yarn, both of said members being 55 provided with aligned transverse scraping edges, and the movable member being yieldably urged against the yarn by a force materially less than the weight of the movable member.
- 60 4. A yarn cleaner for removing particles from a traveling yarn, comprising opposed movable members at opposite sides of the 65 yarn, at least one of which is provided with transverse scraping edges, and means for

yieldably urging each of said members toward the other.

5. A yarn cleaner for removing particles from a traveling yarn, comprising a plurality of pairs of scraping blades, each pair having opposed scraping edges between which the yarn is drawn, and a mounting for said blades permitting a separating movement between the scraping edges of each pair of blades in a direction perpendicular to the line of travel of the yarn, and means for yieldably urging the scraping edges of one of each pair of blades against the yarn with a force so slight that the travel of the yarn between the scraping edges causes inward and outward vibration of the blades.

6. A yarn cleaner for removing particles from a traveling yarn, comprising a plurality of pairs of transverse blades having opposed scraping edges between which the yarn is drawn, the blades of each pair lying in a common plane, and a mounting for said blades permitting a separating movement of the blades of each pair in the common plane of said blades, and means for yieldably urging one blade in each pair against the yarn.

7. A yarn cleaner for removing particles from a traveling yarn, comprising a frame having relatively movable side bars, opposed transverse blades projecting from the inner surfaces of the side bars, one of said bars being yieldably urged toward the other with a force so slight that it and the blades which it carries are set into vibration by the movement of the yarn.

In testimony whereof I have hereunto set my hand.

LOUIS B. HASBROUCK.
